UNITED STATES PATENT OFFICE.

CHARLES F. BEMIS, OF MINNEAPOLIS, MINNESOTA.

STORM-SASH FASTENER.

1,096,811.

Specification of Letters Patent. Patented May 12, 1914.

Application filed May 31, 1913. Serial No. 770,846.

To all whom it may concern:

Be it known that I, CHARLES F. BEMIS, a citizen of the United States, residing at Minneapolis, in the county of Hennepin and State of Minnesota, have invented a new and useful Improvement in Storm-Sash Fasteners, of which the following is a specification.

The object of this invention is to provide a storm sash fastener which is simple and inexpensive in construction and which is adapted to open a storm sash automatically by the opening of one of the slideable window sashes. While primarily intended for such operation my improved fastener may be used to hold the storm sash open irrespective of the movement of the slideable window sashes whereby ventilation may be secured through the window casing by opening the upper slideable window sash.

By the use of my invention the storm sash is adapted to be held in open position without rattling in the wind and is further adapted to be held closed and locked in tight condition to prevent air from entering through the window casing when the lower slideable window sash is closed. My improved fastener is further adapted to be easily and quickly attached for use and detached when not in service.

In the accompanying drawing forming part of this specification, Figure 1 is a vertical transverse section when the storm sash is open; Fig. 2 is a similar view when the storm sash is closed, the broken line position of the sash and its fastener indicating the open position; Fig. 3 is an enlarged detail illustrating the fastener, and Figs. 4, 5 and 6 are fragmentary detail views of parts of my improved fastener.

In the drawing A represents the window casing, B and C, two window sashes which are mounted in said casing and adapted to slide vertically in the usual manner and D a storm sash which is adapted to be hinged to the upper portion of the casing A by separable hinges 2 of the usual construction, whereby the storm sash is adapted to swing in and out at its lower end either to close in the window casing or open it as illustrated in Figs. 1 and 2. The storm sash is adapted to be held in closed and open positions by means of my improved fasteners such as E, one or more being employed and disposed on either side of the casing. Each of the fasteners employed consists of a pair of levers

3 and 4 of equal length, said levers being pivoted together at their ends and to a link 5 by means of the pivot bolt 6. The free ends of the levers 3 and 4 from the pivot connection are respectively fastened to the side of the window casing and to the lower slideable window sash by pivot connections at 7 and 8. The pivot connection 7 as illustrated is in the form of a screw passing permanently into the side of the casing and the pivot connection 8 is in the form of a button 9 mounted upon the bracket 10 which is adapted to be fastened to the lower slideable window sash by means of screws or nails 11. The end of the lever 4 is provided with a longitudinal slot 12 through which said lever may be passed into engagement below the button 9. The free end of the link 5 is pivotally secured by the fastening 13 to the inner surface of the storm sash D, and as the lower slideable window sash is raised or lowered the storm sash D is moved outwardly or swung in and closed automatically in the window casing, the open and closed positions being clearly illustrated in Figs. 1 and 2 of the drawings. The three parts 3, 4 and 5 in effect are three toggle levers or links pivoted together at a common point, the free end of lever 3 being permanently secured to the window casing, the free end of lever 4 being detachably secured to the lower slideable window frame and the free end of lever 5 permanently secured to the storm sash. The operation of opening and closing the storm sash is thus automatic with the opening and closing of the lower slideable window sash. The toggle levers 3 and 4 co-acting with the link 5 produce a strong leverage upon the storm sash during the movement of the lower slideable window sash.

When it is desired to hold the storm sash in open position permanently irrespective of the movement of the lower slideable window sash, the lever 4 may be detached from its pivot connection 8 by turning the button 9 and withdrawing the lever 4 through the slot 12. The slotted end of lever 4 may then be connected to the window sash in permanent position by engaging the lever over a button such as 14 secured on the side of the window casing by means of the screw 15. The full line position shown in Fig. 1 illustrates the storm sash rigidly secured to the window casing to hold the storm sash in open position. When used in this manner

the upper slidable window sash may be opened for ventilating while the lower slid-
able window sash remains closed and the
storm sash open.

5 In accordance with the patent statutes, I have described the principles of operation of
my invention together with the apparatus
which I now consider to represent the best
embodiment thereof but I desire to have it
10 understood that the construction shown is
only illustrative and that the invention can
be carried out by other means and applied
to uses other than those above set forth within
the scope of the following claims.

15 Having described my invention, what I
claim as new and desire to protect by Letters Patent is:—

1. The combination with a window casing, a window sash slidable in said casing,
20 a storm sash hinged on said casing and a fastener for said storm sash comprising
three links pivoted together at a common
point, the free end of one link being secured to said window casing, the free end
25 of another link secured to said storm sash
and a free end of the remaining link secured
to said slidable window sash whereby the
movement of said slidable window sash in

said window casing automatically opens or
closes said storm sash in said casing. 30

2. In combination with a window casing,
a pair of lower and upper window sashes
slidably mounted in said casing to move up
and down, a storm sash hinged on said cas- 35
ing to swing out at its lower end and a fas-
tener comprising three links pivoted to-
gether at a common point, the free end of
one link being pivoted to said window cas-
ing, the free end of another link being piv- 40
oted to said storm sash and the free end of
the remaining link being adapted to be de-
tachably secured either to said lower slid-
able window sash or to said window cas-
ing, whereby said storm sash may be made 45
to open and close automatically with the
opening and closing of said lower slidable
window sash or said storm sash may be rig-
idly held in open position free of the move-
ment of said lower slidable window sash.

In testimony whereof, I have signed my 50
name to this specification, in the presence of
two subscribing witnesses.

CHARLES F. BEMIS.
